UNITED STATES PATENT OFFICE.

GEORGE W. HINCHMAN, OF GLENWOOD, INDIANA.

MOWING-MACHINE.

SPECIFICATION forming part of Letters Patent No. 686,405, dated November 12, 1901.

Application filed June 11, 1901. Serial No. 64,139. (No model.)

To all whom it may concern:

Be it known that I, GEORGE W. HINCHMAN, a citizen of the United States, and a resident of Glenwood, in the county of Rush and State 5 of Indiana, have invented a Mowing-Machine, of which the following is a specification.

The object of this invention is to provide simple and effective mechanism for driving the cutter-bar of a mowing-machine, whereby 10 the rotary motion of the axle upon which the ground-wheels are mounted is converted into a reciprocating motion applied directly to the cutter-bar through the intervention of a pair of tappet-wheels mounted on the main axle; 15 a rocking bar having a cross-head which is struck by the tappet-wheels alternately to rock said bar, said rocking bar having a crank on its outer end by which it is connected to the rod which operates the cutter-bar, and 20 means for throwing the parts out of operation.

The following specification enters into a detail description of my invention, reference being had to the accompanying drawings, and to letters of reference thereon, which indicate 25 the different parts, and what I claim in the particular construction and combination is more specifically set forth in the appended claims.

In the drawings, Figure 1 is a plan view of 30 a mowing-machine constructed in accordance with my invention. Fig. 2 is a longitudinal sectional view on the line 2 2 of Fig. 1. Fig. 3 is a detail view illustrating the gearing between the tappet-wheels and rocking bar. 35 Fig. 4 is a detail view of the sectional rocking bar.

Referring to the drawings, A designates the axle of the mowing-machine, upon the ends of which are fixed the ground-wheels B B in 40 order that the said axle may turn with the ground-wheels and serve to operate the cutter-bar in the manner hereinafter described.

Mounted upon the axle A is a suitable frame C, which provides a support for the 45 driver's seat c' and is extended forward, as shown, to form a bearing for the rocking bar, through which motion is transmitted to the cutter-bar of the cutting apparatus.

D D designate tappet-wheels which are located upon the central portion of the axle A and are fixed thereto in any suitable manner. These tappet-wheels face each other, and be-

tween the same, upon the shaft A, is loosely mounted a bracket E, having lugs e² e², through which passes a sectional rocking bar F F', the 55 said rocking bar being supported at its outer end by the extension c of the frame C. This rocking bar is made up of two parts or sections F and F', the tubular section F' being 60 slideable upon the rear end of the section or bar F, the said sections being connected by an ordinary spline or feather, as shown in Fig. 3. At the forward end of the tubular section F' is a cross-head f, which is engaged by the tappets d' on the tappet-wheels D, and at the 65 rear end of said section is a collar f', fixed thereon and connected by yoke s to a hand-lever S. Upon the rear end of the tubular section F' of the rocking bar, in advance of the aforesaid collar f', is an adjustable collar 70 f², between which and the lug e² is interposed a helical spring t, which spring serves to keep the cross-head in line with the tappets, and said cross-head may be moved out of operation by moving the hand-lever S forward, sliding the 75 tubular section F' upon the bar F. It will be here noted that the arms of the cross-head and the tappets are beveled, as shown in Fig. 3, so that in case of an accident to the cutting apparatus by reason of anything catching between the fingers the cross-head would be 80 moved forward against the force of the spring, and thereby prevent serious injury to the machine. The adjustable collar f² provides for increasing and diminishing the tension of 85 the spring. The tappets engage the cross-head alternately, so as to rock the bar, and this rocking movement of the bar is converted into a reciprocating motion, imparted to the cutter-bar L by means of a crank H, to which 90 the connecting-rod I is attached.

The finger-bar M of the cutting apparatus may be hinged to the forward part of the frame C in the usual manner and any suitable lever mechanism provided for elevating 95 the cutting apparatus out of operative position. The machine is also provided with a tongue a and with an ordinary shoe a'.

From the foregoing description, in connection with the accompanying drawings, the 100 operation of the driving mechanism for the cutter-bar will be readily understood, for the rotation of the axle as the machine passes over the field will turn the tappet-wheels D D, and

the tappets of said wheels respectively engaging first one arm of the cross-head and then the other will rock the bar and by means of the crank will impart a reciprocating motion to the cutter-bar. This mechanism provides a positive operation, and comprising but few parts reduces the friction to a minimum. The driving mechanism for the cutter-bar can be readily and conveniently thrown out of operation, and by providing the yielding connection between the cross-head and rocking bar the parts are relieved of any undue strain in the event anything should catch between the fingers of the cutting apparatus.

15 The tappet-wheels and interposed parts may be housed by a suitable casing.

Having thus described my invention, I claim—

20 1. In a mowing-machine, the combination with the axle, of tappet-wheels mounted thereon, a rocking bar extending between the tappet-wheels and comprising two sections slidable one upon the other, a cross-head mounted upon the slidable section, and a spring adapted to hold the cross-head nor-

30 mally in line with the tappets, the rocking bar having a crank to which the connecting-rod of the cutting mechanism is attached, substantially as shown and described.

2. In a mowing-machine, the combination with the axle, of tappet-wheels mounted thereon, a rocking bar extending between the tappet-wheels and comprising two parts slidable one upon the other, a cross-head mounted on the slidable section of the rocking bar, a grooved collar connected to said slidable section, a hand-lever connected to the collar, an adjustable collar mounted upon the slidable section of the rocking bar, and a spring 35 interposed between said adjustable collar and a stationary part of the machine, the rocking bar having a crank by which it is connected to the connecting-rod of the cutting mechanism, substantially as shown and described. 40

45 In testimony whereof I affix my signature, in the presence of two witnesses, at Glenwood, Indiana, April 1, 1901.

GEORGE W. HINCHMAN.
